UNITED STATES PATENT OFFICE.

JAMES H. SHAW, OF GREENSBORO, NORTH CAROLINA.

COMBINED MANIFOLDING BILL AND ENVELOP.

No. 893,202.

Specification of Letters Patent. Patented July 14, 1908.

Application filed December 28, 1905. Serial No. 293,645.

To all whom it may concern:

Be it known that I, JAMES H. SHAW, a citizen of the United States, residing at Greensboro, in the county of Guilford and 5 State of North Carolina, have invented a new and useful Combined Manifolding Bill and Envelop, of which the following is a specification.

This invention relates to a combined mani- 10 folding bill and envelop.

The object of the invention is in a ready and practical manner to obviate mistakes and loss of money arising from the carelessness or dishonesty of drivers in delivering 15 goods and collecting therefor; furthermore to render it possible to keep a tab on the driver whereby mistakes of any kind that may be made shall be instantly detected.

With the above and other objects in view, 20 as will appear as the nature of the invention is better understood, the same consists, generally stated, in an article of the class described embodying in its construction, an envelop constituting a customer's slip, a 25 driver's return slip and a merchant's slip, each being a duplicate of the others as to the matter written thereon, whereby should an error occur in the entries on any one of the slips detection is almost inevitable.

30 The invention consists further in the novel construction and combination of parts of a combined manifolding bill and envelop, as will be hereinafter fully described and claimed.

35 In the accompanying drawings forming a part of this specification, and in which like characters of reference indicate corresponding parts: Figure 1 is a view in perspective of one form of the invention, viewed from 40 the front. Fig. 2 is a similar view viewed from the rear. Fig. 3 is a plan view of the blank from which the article exhibited in Figs. 1 and 2 is made. Fig. 4 is a perspective view of a modified form of the invention. Fig. 5 is another view of the envelop 45 shown in Fig. 4, the flaps being raised and the manifolding sheet in position. Fig. 6, is a view of the envelop shown in Figs. 1 and 2 with the manifolding sheet in position.

50 In the form of the invention shown in Figs. 1, 2 and 3, the article is made from a single sheet of paper, comprising three connected members 1, 2 and 3, the member 1 being the merchant's slip, the member 2 the driver's 55 slip, and the member 3 the back of the envelop, the face of which is formed by an ex-

tension 4 projecting laterally from the member 3, and constituting the customer's slip. Each of these slips is appropriately ruled to receive entries, and bear printed legends such, for instance, as the name of the firm using the device, a serial number, the amount of change to be sent, the amount to be collected, and any other data that it may be desired to exhibit in carrying the invention into effect. The extension 4 has a gummed edge 5 that is sealed around the back or member 3, as shown in Fig. 2, and a flap 6 for closing the mouth of the envelop formed by the member 3 and extension 4. The inner side of the envelop has a paraffin lining 7 which may be produced by coating the member 3 and extension 4 with paraffin, or, as shown, by pasting a sheet of paraffin paper to the member 3 at 8. The object of this paraffin lining is to prevent articles having gummed surfaces from adhering to the interior of the envelop, as it frequently happens that a customer will have a merchant purchase postage stamps and forward them with an order. Some 80 firms use trading stamps that are gummed, and others trade coupons that are similarly gummed, and it frequently happens that these will become stuck together in the driver's pocket and thus become useless. 85 By the provision of the envelop, stamps and other gummed objects may be safely transmitted to the purchaser, along with change for money. The upper portion of the member 2 is provided with a weakened or per- 90 forated line 9 forming in conjunction with the member 3 a tab 10 that is adapted to be sealed to the lower end of the face of the customer's slip 3, and thus seal the lower end of the envelop. The weakened line also per- 95 mits ready detachment of the driver's slip from the customer's slip. The slip 2 is pro- vided near its lower end with a weakened line 11 which will permit ready detachment of the merchant's slip therefrom. In the use of 100 this form of the device, the customer's name and order is written on the merchant's slip and is transferred by interposed carbon or other manifolding material to the slips 2 and 3. Should an order be received by mail, 105 telephone or otherwise, in which a customer requests that change for a certain amount be forwarded with the goods, this change will be inclosed in an envelop along with the trading stamps or the like. Thus, for instance, if a 110 bill came to \$5.30, and the customer requested that change for \$10.00 be forwarded

with the order, \$4.70 will be inclosed in the envelop. When the goods are to be delivered, the slip 1 is torn from the slip 2 and is retained by the merchant, which will serve 5 as a check upon the driver. When the goods are delivered to a customer, the driver will detach the slip 2 from the slip 3, and return this with the collection to the merchant. Should any discrepancy exist, it can instantly 10 be detected at the time.

As a further feature of novelty, the extension 4, may have its bottom portion printed to represent a coupon 12 having any specified value that the merchant may elect to attach 15 to it, and this will be retained by the customer and employed according to directions furnished.

In the form of the invention shown in Fig. 4, the envelop 13 and driver's return slip 14 will be made from one piece of paper, and the merchant's slip 15 will be pasted or otherwise secured to the driver's slip. Both of these slips are provided with weakened lines 16 which will permit the upper portion of the 20 driver's slip to be sealed to the face of the envelop, thus to seal its bottom and also to permit ready detachment of the two slips in the manner described.

The forms of the invention herein shown 25 and described, are two of many that may be employed and as other modifications will

be obvious, detailed illustration thereof is deemed unnecessary.

I claim:—

1. An envelop having an open end sealing flap and provided with a downwardly extending slip, said slip being creased near the bottom edge of said envelop and also formed below said crease with a weakened line portion for forming a tab for closing the lower 40 end of the envelop, said extension also having at its lower edge an additional extension provided with a weakened line portion, and a manifolding sheet insertible between said slip and one wall of said envelop. 45

2. An envelop having an open end sealing flap and partly formed of a lateral extension thereof overlying the back portion of said envelop and secured at its otherwise free edge to said back portion, said envelop being provided with a downwardly extending strip loosely overlying the wall formed by said lateral extension, and detachably joined to the envelop, and a manifolding sheet insertible between said slip and said wall. 50

In testimony that I claim the foregoing as my own, I have hereto affixed my signature in the presence of two witnesses.

JAMES H. SHAW.
